AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

BOBBIN RELEASE FOR WEFT-REPLENISHING MECHANISM

Application filed June 8, 1928. Serial No. 283,977.

This invention relates to improvements in bobbin releasing devices more particularly for multicolor weft replenishing mechanisms and it is the general object of the invention 5 to provide a mechanism of this type which will operate when the lay is in its rearward position so that an untransferred bobbin will be released at a time when it may fall into the bobbin can with as little interference as 10 possible.

When a bobbin has once reached transfer position in a multicolor weft replenishing loom there is ordinarily no way to restore it to the stack of bobbins from which it was delivered should the shuttle be improperly placed and therefore unable to accept the new bobbin. Under these conditions the bobbin must be released, otherwise there would be danger that it would be inserted in the wrong 15 shuttle should the shuttles shift on the next pick of the loom.

The device at present employed to release the bobbin is that operating on the principle set forth in patent to Lauzon No. 1,261,563. 20 In that patent provision is made for keeping the bobbin support in open position at all times except when it is desired to transfer a new bobbin, at which time the support is moved to bobbin supporting position to hold the bobbin properly under the transerrer arm. As the magazine is reset with the lay 25 on front center the bobbin support is moved rearwardly or to its bobbin releasing position, the effect of which is to drop a bobbin 30 directly on the shuttle in the shuttle box thereunder.

Such an operation occasionally results in the catching of the bobbin by some part of the lay with resultant breakage and it is an 35 important part of the present invention to retain the general principle of the Lauzon patent but delay movement of the bobbin support to releasing position until the lay has reached its rearmost position after transfer.

The usual weft replenishing mechcanism for multicolor weft replenishing looms employs a bobbin support of the type shown in patent to Ryon No. 1,366,950 which incorporates the Lauzon principle and it is a more 40 particular object of my present invention

to add to the bobbin support of the Ryon patent a member which will cooperate with the Lauzon setting stud, said part to be moved to its final position to effect movement of the support by the lay on its backward movement. 55

It is a still further object of my present invention to provide means for moving the bobbin support actuating member to a position where it will clear the lay as the latter moves back and forth in the loom. 60

With these and other objects in view which will appear as the description proceeds, my invention resides in the combination and arrangement of parts hereinafter described and set forth in the claims. 65

In the accompanying drawings, wherein a convenient embodiment of my invention is set forth,

Fig. 1 is a side elevation of a multicolor weft replenishing mechanism having my invention applied thereto as seen from the interior of the loom. 70

Fig. 2 is an enlarged view looking in the direction of arrow 2, Fig. 1.

Fig. 3 is a view similar to Fig. 2 but with 75 certain parts removed to show more clearly the relation of the spring which operates the knuckle joint,

Fig. 4 is a detailed side elevation of a portion of the replenishing mechanism showing 80 the bobbin support as seen from a direction opposite that in which Fig. 1 is taken, the parts being in normal or bobbin releasing position,

Fig. 5 is a view similar to Fig. 4 but with 85 the parts in bobbin supporting position, and

Fig. 6 is a horizontal section on line 6—6 of Fig. 5.

Referring particularly to Figs. 1, 2 and 3 the weft replenishing mechanism 10 is shown 90 as having a plurality of vertical slides 11 which control the release of bobbins from the several stacks. The particular slide 11 which is to be called into action is selected by the so-called color slide 12, a bell crank lever 13 positioning said color slide longitudinally relatively to the vertical slides 11. The lever is pivoted to a stand 14 secured to the rear of the magazine frame 10. 95

Pivots connected as at 15 to the bracket 100

14 is a shuttle feeler carrier 16 to which is secured a pressed metal shuttle feeler 17 the office of which is to detect for the shuttle and revoke or prevent transfer should the shuttle be improperly boxed. The shuttle feeler carrier has secured thereto a stud S which extends substantially parallel to the lay L.

The raising and lowering of the shuttle feeler 17 and its carrier is effected through a vertical rod 18 which is connected as at 19 to the shuttle feeler carrier. The upper end of said rod 18 is connected to an arm 20 secured to a rock shaft 21 to the forward end of which is secured an arm 22. A rectangular block 23 is pivotally supported by the arm 22 and extends through a slot 24 formed in arm 25 of lever 26 pivoted as at 27 to the upper end of the frame 10. A depending rod 28 secured to the lever 26 controls the trans-
ferrer latch not shown.

A comparatively strong compression spring 29 is interposed between the lever 26 and the block 23 and operates to hold said lever together with the arm 22 definitely in one of two positions. Under normal conditions said spring will operate to hold the parts as shown in Fig. 2 with adjustable stop screw 30 carried by arm 25 in engagement with a fixed part of the frame 10 such as a lug 31 which receives one of the upper tie rods for the magazine. When the lever 26 is moved in a counter-clockwise direction around stud 27 from the position shown in Fig. 2, a second stop screw 32 will engage the lug 31 to limit movement of said lever and arm 22 under influence of the spring 29. In this way the spring operates to hold the arm 20 and shaft 21 to which it is secured definitely in two different angular positions and it is in this way that the position of the shuttle feeler carrier 16 and therefore the stud S is determined.

Referring particularly to Figs. 4, 5 and 6 I have shown a particular method of supporting the bobbin where it will be seen that a stand 40 secured to the rear part of the weft replenishing frame 10 carries a stud 41 to which is pivoted a link 42 having set screw 43 therein. Said set screw acts on a pin 44 carried by the upwardly projecting arm 45 of the bobbin supporting member 46. The latter is pivoted as at 47 to the lower end of a suspension arm 48 mounted on a fixed tie rod 49 forming a part of the weft replenishing mechanism. As shown in Fig. 5, a torsion spring 50 surrounds the tie rod 49 and has one end thereof secured to the arm 48 and the other end secured to a collar 51 secured in adjusted angular position to the rod 49.

The effect of the torsion spring is to move the arm 48 forwardly or in a clockwise direction around tie rod 49 as viewed in Figs. 4 and 5. Stop screw 52 engages a part of the frame 10 to limit movement of the suspension arm 48 to the left as viewed in Figs. 4 and 5.

under action of spring 50. A lug 53 formed as part of arm 48 receives the upper end of a light tension spring 54 the lower end of which is connected to arm 45 to hold the pin 44 normally against screw 43. The magazine has a forward butt support 55 which cooperates with the arm 46 to support the head or butt of a bobbin in transfer position. As will appear hereinafter the spring 50 is weaker than spring 29.

The matter thus far described is substantially the same as shown in the previously mentioned patents and for a further description of the structure and operation of the magazine reference may be had to patent to Ryon No. 1,030,748.

As previously stated it may happen that a bobbin will remain in the position shown in Fig. 5 after the time allotted for transfer due to an improper boxing of the shuttle and under these conditions it is essential that the bobbin be released. My present invention relates to means for effecting this release at a later time in the cycle of the pick than is possible in the Lauzon patent and in carrying my invention into effect I provide the arm 48 with a depending extension 60 which has pivotally connected thereto as at 61 a setting lever 62 the rear end of which has a rearwardly and downwardly inclined arm 63. The forward end 64 of the setting lever is provided with a notch which is defined by a rearwardly and downwardly extending face 65 which intersects with a rearwardly and upwardly extending surface 66, said notch being designated herein at 67. I form the upwardly and rearwardly extending surface 66 so that the upper portion thereof which terminates in the notch 67 is preferably nearer the axis of the stud 61 than is the lower portion thereof. In other words the surface 66 is preferably inclined toward the axis of the setting lever. I do not wish to be limited strictly to this design of the notch, although I find it convenient.

A light tension spring 68 is interposed between a portion of the arm 45 as at 69 and the setting lever and tends normally to move the setting lever in a left hand direction as viewed in Fig. 5. Such motion is limited by a stop 70 carried by the extension 60 and engaging a portion of the setting lever so as to hold the latter in the position shown in Fig. 5.

That portion of the stud S which lies under the forward end of the setting lever may be formed with an angular or knife edge 71 as shown clearly in Figs. 4 and 5, said knife edge being designed to enter the notch 67.

Under normal conditions the parts are in the position shown in Fig. 4 with supporting arm 46 in rearward position and the shuttle feeler 17 in raised position, the stud S being in its highest position and located in the notch 67. When a transfer is about to take place the rod 18 will be depressed to move the

stud S downwardly. The stop 70 will operate to prevent the arm 64 of the setting lever from following the stud downwardly so that as the rod 18 descends the knife edge 71 will be disengaged from the notch 67. As soon as stud S moves out of controlling position with respect to the setting lever 62 the torsion spring 50 will move the arm 48 and the bobbin support 46 to the left until such motion is arrested by stop screw 52. The support 46 will come to rest in such a position that the distance between the same and the forward bobbin support 55 is less than the diameter of the bobbin B. A bobbin will then be released from one or another of the stacks of bobbins in the magazine and will move to the position shown in dot and dash lines in Fig. 5 to await transfer.

If the shuttle should not be properly boxed the feeler 17 will be moved upwardly before the lay reaches its extreme forward position to restore the parts to the position shown in Fig. 2, thus lifting the stud S to the position shown in Fig. 4 in full lines. By the previous movement of the support 46 to the left under influence of the torsion spring 50 the setting lever 62 was moved over the stud S so that as the latter is raised it will engage the under side of arm 64 of the setting lever and move the same to the dotted line position shown in Fig. 5. This operation will take place while the lay is nearing front center on the pick when transfer should take place and the spring 29 will be of sufficient strength to hold the stud S in the dotted line position shown in Fig. 5. The setting lever 62 is therefore rocked about its axis to move the arm 63 thereof to the low position indicated in dotted lines in Fig. 5.

As the loom continues to operate the lay L will move rearwardly or from the full line position shown in Fig. 5 to the right to carry bunter 72 into engagement with the arm 63 of the setting lever and move the latter rearwardly. By reason of the fact that the spring 29 has a stronger effect than that of torsion spring 50 the latter will be strained and the stud S will be able to remain in raised position with the arm 64 sliding across the top thereof. During the time that the bunter 72 is in engagement with the lever 63 the support 46 will be moved to the right as viewed in Fig. 5 and will ultimately assume the position shown in Fig. 4, where it will be spaced sufficiently from the forward bobbin support 55 to release the bobbin. This condition takes place, it will be understood, when the lay is practically in its rearmost position so that the bobbin may be discharged without interfering with the lay.

During the backward movement of the setting lever the forward end of the arm 64 will ultimately pass over the knife edge 71, at which time the light spring 68 will move the setting lever in a counter-clockwise direction

around the stud 61 until the knife edge is seated in the notch 67 or movement of the setting lever is arrested by the stop 70. This additional motion of the setting lever 62 under action of the tension spring 68 will move the arm 63 an additional amount, so that the same will be out of the path of the bunter 72 as the lay moves back and forth. By reason of the spring 68 and the surface 66 cooperating with the knife edge 71 I am therefore able to move the setting lever to a position where it will clear the lay, the inclination of the surface 66 assisting the spring 68 in rocking the setting lever. The parts thus restored to normal position are ready for the repeated indication which will be given due to the failure to transfer, should the previously indicated shuttle remain in action and again be presented under the magazine.

From the foregoing it will be seen that I have provided a simple setting lever which may be added to the form of bobbin support generally used, said setting lever being operated on the backward stroke of the lay to move the bobbin support to bobbin releasing position so that an untransferred bobbin may be ejected from the magazine at a time when the lay cannot engage the same to cause damage either to the magazine or the bobbin. It will further be seen that I have formed that portion of the setting lever which engages the stud S so as to retain the parts in bobbin releasing position so long as the stud S remains raised after the first complete rearward movement of the lay following a revocation of transfer. It will also be seen that the light spring 68 together with the surface 66 operates to hold the setting lever out of engaging position with the bunter 72. While I have set forth the fact that the surface 66 is to be inclined slightly toward the axis of the stud 61 yet if the spring 68 be sufficiently strong I will not necessarily be held to this relation of the parts.

Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism for looms, a lay, a pair of movable jointed bobbin supporting elements, means normally holding said elements in open bobbin releasing position, and a resetting device carried by one of the elements and moving therewith to be engaged and moved by the lay to move said elements to open bobbin releasing position.

2. In a weft replenishing mechanism for looms, a lay, a suspension arm movable about a fixed pivot, a movable bobbin engaging support pivoted to the arm, a resetting device pivoted to the suspension arm and positioned

to engage the lay as the latter moves rearwardly to be moved by the lay to cause the latter to effect rearward movement of the bobbin support and move the same to open bobbin releasing position.

5. 3. In a weft replenishing mechanism for looms, a lay, a pair of movable bobbin supporting elements which are jointed together, one of said elements being movable about a fixed pivot, a resetting device carried by the latter element and movable therewith to a position to engage the lay to cause the latter to move the elements to open bobbin releasing position as the lay moves rearwardly.

10. 4. In a weft replenishing mechanism for looms, a lay, a suspension arm movable about a fixed pivot, a bobbin support moving with and pivoted to the suspension arm, a setting device pivoted to the suspension arm, and 20 means movable under control of the replenishing mechanism and effective when in normal position to engage the resetting device to hold the bobbin support in open bobbin releasing position, said means when moved by the replenishing mechanism releasing the resetting device and the latter being engaged by the lay as the lay nears the end of its backward stroke to be moved rearwardly by the lay to carry the bobbin support rearwardly.

25. 5. In a weft replenishing mechanism for looms, a lay, a suspension arm movable about a fixed pivot, a bobbin support moving with and pivoted to the suspension arm, a setting device pivoted to the suspension arm, and 35 means movable under control of the replenishing mechanism and effective when in normal position to engage the resetting device to hold the bobbin support in open bobbin releasing position, said means when moved by the replenishing mechanism releasing the resetting device and the latter being engaged by the lay as the lay nears the end of its backward stroke to be moved rearwardly by the lay to carry the bobbin support rearwardly, 40 said resetting device being moved by the lay into holding engagement with the means.

45. 6. In a weft replenishing mechanism for looms, a lay, a pair of movable pivoted elements one of which moves about a fixed axis 50 and the other of which has provision for engaging and supporting a bobbin, a resetting device pivotally mounted to one of the elements, and means under control of the replenishing mechanism normally engaging the resetting device normally to hold said elements 55 in open bobbin releasing position, said means being movable by the replenishing mechanism to release the resetting device, whereby the elements are movable to bobbin supporting 60 position, the lay on the backward stroke thereof engaging the resetting device to move the latter together with the elements rearwardly and to establish holding relation between the resetting device and the means.

65. 7. In a weft replenishing mechanism for

looms, a lay, a suspension arm movable about a fixed axis, a bobbin support pivoted to and moving with the suspension arm, a setting lever pivoted to the suspension arm, and a stud movable from normal to transfer position by the replenishing mechanism prior to the time of transfer, said stud when in normal position engaging the setting lever to hold the latter together with the bobbin support in open bobbin releasing position, said stud 70 when moved by the replenishing mechanism to transfer position to be disengaged from the setting lever, whereupon the latter together with the bobbin support is free to move to bobbin supporting position.

75. 8. In a weft replenishing mechanism for looms, a lay, a suspension arm movable about a fixed axis, a bobbin support pivoted to and moving with the suspension arm, a setting lever pivoted to the suspension arm, and a stud movable from normal to transfer position by the replenishing mechanism prior to the time of transfer, said stud when in normal position engaging the setting lever to hold the latter together with the bobbin support in open bobbin releasing position, said stud 80 when moved by the replenishing mechanism to transfer position to be disengaged from the setting lever, whereupon the latter together with the bobbin support is free to move to bobbin supporting position, said stud 85 when being returned to normal position engaging the setting lever to move the same into the path of the lay, the lay to engage the setting lever as said lay nears the limit of its rearward movement to move the bobbin support to open bobbin releasing position and to effect holding engagement between the setting lever and the stud.

90. 9. In a weft replenishing mechanism for looms, a lay, a pair of movable bobbin supporting elements pivotally connected together, one of said elements movable about a fixed axis and the other of said elements having means for supporting a bobbin, a setting device pivoted to one of the elements, 95 means movable from normal to transfer position by the replenishing mechanism, said means normally engaging the setting device to hold the latter out of the path of the lay, said means when being moved from transfer back to normal position engaging the setting device to move the same into the path of the lay, whereupon the latter in its rearward stroke engages the setting device to move the bobbin supporting element to open bobbin releasing position and at the same time effect holding engagement between the means and the setting device.

10. 10. In a weft replenishing mechanism for looms, a lay, a suspension arm, a bobbin support pivoted to and moving with the suspension arm, a setting lever pivoted to the suspension arm, means defining a notch in said setting lever, a stud movable by the replenishing 115 120 125 130

mechanism from normal to transfer position, said stud normally being located in the notch to hold the setting lever together with the bobbin support in open bobbin releasing position, said stud when moving from normal to transfer position being disengaged from the setting lever, whereupon the setting lever together with the supporting arm and bobbin support are free to move to bobbin supporting position, and said stud when being returned to normal position from transfer position moving the setting lever into the path of the lay, whereupon the latter at the end of its rearward stroke will engage said setting lever to move the same together with the bobbin support rearwardly and simultaneously effect return of the stud into the notch in the setting lever.

In testimony whereof I have hereunto affixed my signature.

AUGUSTIN J. CHEVRETTE.
